Term of patent 14 years

Int. Cl. D29—02

U.S. Cl. D72—1 H

Fig. 1

Fig. 2

FIG. 1 is a front perspective view of a signal showing our new design in its erect position, a rear perspective view being identical; and

FIG. 2 is a front perspective view of the triangular signal device in its folded condition.

The hexagonal faceting is partially shown in FIGS. 1 and 2 for convenience of illustration, it being understood that the faceting is uniformly continuous over the areas indicated. The bottom horizontal support member is broken away in FIG. 1 for convenience of illustration.

We claim:

The ornamental design for a signal, substantially as shown and described.
